UNITED STATES PATENT OFFICE.

JAMES W. BOILEAU, OF DENVER, COLORADO, ASSIGNOR OF ONE-HALF TO JAMES B. KNOBLOCK, OF DENVER, COLORADO.

APPARATUS FOR TREATING ORE.

No. 866,570.

Specification of Letters Patent.

Patented Sept. 17, 1907.

Application filed May 5, 1903. Serial No. 155,761.

To all whom it may concern:

Be it known that I, JAMES W. BOILEAU, a native-born citizen of the United States, residing at Denver, Denver county, State of Colorado, have invented certain new and useful Improvements in Apparatus for Treating Ores; and I do hereby declare the following to be a full, clear, and exact description of the invention, such as will enable others skilled in the art to which it appertains to make and use the same.

10 My invention relates to improvements in apparatus for the treatment, in a ready, simple and effective manner, of ores which it is desired to roast, and embraces means whereby, at the same time, said ores may be subjected to the influence of oxidizing or carbonating agents, as may be desired by the operator.

As is well known, metalliferous ores hold their values in varying combination and require a method of treatment consonant with their peculiar chemical formation. Some ores, moreover, contain certain volatile impurities which, if allowed to come in contact with the metal of the apparatus, have a very destructive effect. The moisture contained in the crude state, coming into union with the impurities given off by the ore in the process of roasting, form, in some cases, sulfuric acid which is very injurious.

My invention, then, embraces means whereby the ore is subjected to preliminary treatment at a temperature sufficiently high to drive off the moisture and to eliminate by volatilization those ingredients which would be injurious if brought into contact with the iron structure of the roasting apparatus; supplemental means whereby such volatilized ingredients may be collected and utilized, if desired; means whereby the ore may be roasted at gradually increasing temperatures; means whereby, during the process of roasting, the ore will be thoroughly agitated and subjected to the influence of air, oxygen, or such other gaseous agents as may be best adapted to the particular ore under treatment; and means for minimizing the transmission of heat between the parts of the apparatus and providing for the ready renewal of the same.

In the accompanying drawings, I have illustrated a preferred embodiment of my invention, and although it will be obvious that certain modifications of form and arrangement will suggest themselves to the skilled operator and mechanic, such modifications come well within the spirit of my invention as disclosed and claimed, and I do not, therefore, desire to be limited to the exact construction and arrangement shown.

50 In these drawings: Figure 1 is a side elevation of the apparatus with one wall of the roaster and drier removed in order to show the arrangement of the parts; Fig. 2 is an enlarged cross section on the line x—x of

Fig. 1. Fig. 3 is an end elevation of the apparatus; and Fig. 4 is a detail showing certain parts on an enlarged scale.

Referring to the drawings more in detail, the roaster consists of an inclined chamber 1, preferably disposed at an angle of about 30 degrees to the horizontal, and communicating at its lower extremity with the receptacle 2 for the roasted product. Adjacent to this receptacle and beneath the lower extremity of the roasting chamber 1 is a furnace 3 provided with a stack 4 extending beneath the inclined roasting chamber and serving to carry the heated products of combustion the full length thereof, and to discharge the smoke into the flue 5 while permitting the larger portion of the heat to enter and traverse the drying chamber. On either side of and adjacent to the furnace are arranged gas generators 6, provided with the usual doors for the insertion of fuel, removal of ashes, etc. These gas generators will in some cases be used for the heating of air supplied by the fans 36 or for superheating steam supplied by the pipes 37. The pipe 7 leads from the gas generators beneath the chamber 1 and discharges through an elbow into the lower portion of the drying chamber, from whence the heated gases, mingling with those from the furnace, pass upward through the drying chamber in contact with the material descending therein. This pipe 7 is controlled by suitable valves, and is also tapped by the branch pipes 8, provided with the valves 9, which communicate with the interior of the roasting chamber in such manner as to subserve an important function to be hereinafter fully described.

The drying chamber 10 is a substantially vertical prolongation of the roasting chamber 1 and is provided with inclined plates 11 by means of which the ore is deflected from side to side in its descent through said chamber. The drying chamber is equipped in its upper portion with the feed screw 12 and spreader 12^a by means of which the ore is fed into the said chamber and egress of gases therefrom effectually prevented.

Tapping the upper portion of the drying chamber is a pipe 13 which leads to the upper portion of a supplemental sealed tank 14 and discharges therein the heated air, gases and fumes from the drying and roasting chambers. The pipe 15 leads from a boiler to the upper portion of this tank 14 and serves to introduce steam for the purpose of condensing the gases and precipitating the fumes introduced thereto. This tank 100 has a funnel-shaped bottom provided with a valve by means of which matters deposited in said tank may be removed. The tank 16 is of a somewhat similar construction and is provided with the pipe 17 by means of which the waste gases are allowed to escape to the outer air. This tank 16 is partially filled with water,

and the pipe 18 leads from the upper portion of the tank 14 and discharges beneath the surface of the water in the tank 16. A pipe 19 leads from the bottom of the tank 16 into a storage tank 20 for the withdrawal 5 of the sulfuric acid or other product formed in said tank according to the nature of the elements introduced thereto.

Referring again to the roasting chamber 1, the same has a lower floor formed of a series of concave shelves 21 merging into an inclined portion 22 connecting in turn with the next concave shelf as at 23. These concave shelves and inclined portions forming the upper and lower walls of the chamber 1 are preferably made of overlapping plates having lip joints to allow for expansion and contraction under the influence of varying degrees of heat, and are so arranged that the parts may be readily renewed.

A series of wheels 24 are mounted within the roasting chamber 1 in such manner as to rotate therein with their peripheries closely adjacent to the upper and lower concave surfaces 21. These wheels are provided with a plurality of peripheral scoops or buckets 25, and are each carried by a suitable shaft 26 passing through the walls of the roasting chamber. Each such 25 shaft (Fig. 2) is provided with an enlargement, or shoulder in the form of a plate 27 which is bolted or otherwise secured to a corresponding plate 28 carried by the supplemental or stub shaft 29. Between the two plates is placed a packing 30 of asbestos or other 30 suitable non-conductor of heat. These shaft enlargements or plates are arranged to rotate with their lower edges within a basin 31 adapted to contain water to minimize the transmission of heat from the main shaft to the stub shaft, boxing and gearing. The supplemental or stub shaft is journaled in a boxing 32 and carries the sprocket wheels 33. The sprocket wheels of the several shafts in the series connect by means of the usual chain belts 34, and one or more of the shafts carrying a main driving pulley 35 operated from any 40 suitable source of power.

The operation of the device is as follows: A fire is started in the furnace 3 and, after the roasting chamber is brought to the desired temperature, the ore is fed by means of the conveyor 12 into the upper portion of 45 the drying chamber 10, and descends through the same, being deflected from side to side by means of the inclined plates 11. In its passage through this drying chamber the ore is brought thoroughly into contact with the heated air coming from the roasting chamber and 50 also with the hot air or other gas from the upper extremity of the pipe 7. By the time the ore reaches the roasting chamber its moisture is thoroughly eliminated and thus the introduction of sulfurous acid and other destructive agents into the roasting chamber is 55 obviated, all the fumes driven off in the roasting chamber as well as those within the drying chamber being carried off by the pipe 13 and deposited within the tanks provided for their reception and utilization. As 60 the ore, thus dried and freed from its easily volatilized constituents, enters the roasting chamber and is deposited upon the first concave shelf in the series, it is picked up by the peripheral scoops 25, and carried over the wheels 24 and allowed to fall upon the inclined approach to the next concave shelf. In its fall from 65 said scoop it is thoroughly impregnated with the gas

discharged from the branch pipes 8 which discharge their contents from either side directly into the falling mass of ore. At this point the ore is subjected to an oxidizing or carbonating action according to the nature of the gas furnished by the generators 6. In the treatment of certain ores, such for instance, as those carrying gold, silver or copper as a sulfid or sulfuret, I prefer to introduce at this point a blast of heated air, or oxygen for the purpose of oxidizing the sulfur in the well known manner. In case the ore carries gold, silver, copper, 70 lead, zinc, antimony bismuth, tin, etc. as a metallic oxid, it is often found advantageous to generate in the chambers 6 a carbon gas such as carbon monoxid and introduce the same in a highly heated condition, together with superheated dry steam, into the falling 75 body of ore, whereupon the same bursts into flame, reducing the ore and escaping as carbon dioxid. Or, such gas may be generated and supplied to the chambers as may be necessary for the formation of sulfuric acid in conjunction with those vapors given off by the 80 ore. It will be seen that by means of the valves and the peculiar disposition of the pipes the exact regulation of the blast is provided for to meet all requirements as to kind of gas and quantity of the same, as 85 well as the temperature at which applied. As the ore passes from one concave to the next, it is taken up by the wheel next in the series and dropped upon the concave next below, and so on, being subjected at 90 each stage to a gradually increasing temperature as it nears the place of deposit 2 at the end of the roasting 95 chamber. The tanks 14, 16 and 20 serve as depositories not only for such metallic values as may be carried over in volatile form and there precipitated, but any values which may be carried over in mechanical suspension are there precipitated and thus saved. 100 Moreover the tank 16 serves for the formation, incidental to the roasting of the ore but none the less efficiently, of sulfuric acid from the volatilized sulfur, gases and steam introduced thereto, which is withdrawn to the tank 20. Thus in the one apparatus, I 105 am able to subject ores to a preliminary drying action, and then to roasting under a constantly increasing temperature, and simultaneously to such oxidizing or reducing action as may be best adapted to the nature of the ore, while at the same time I save the metallic 110 values carried over in volatile form or in mechanical suspension, and utilize the waste products in the formation of sulfuric acid.

While I have herein described my apparatus as employed in the treatment of metalliferous ores, it will 115 be understood that my invention is also adapted to use in connection with the treatment of cement, non-metalliferous ores, lime stone and even to the roasting of grains. Wherefore I do not desire to be understood as using the term "ore" in a narrow sense but as including any raw material which it is desired to subject to a roasting process.

Having thus fully described my invention, what I claim as new and desire to secure by Letters Patent of the United States, is

1. In an apparatus of the character described, a channel, means for heating the same, an ore supply thereto, means for lifting the ore and projecting it forward in line with the channel, and means for discharging heated gas into the ore during its passage through the channel.

2. In an apparatus of the character described, a sloping channel, means for heating the same, an ore supply thereto, means for intermittently picking the ore up carrying it forward in line with the channel and allowing it to fall, and means for discharging gas into the falling ore. 80
5. In an apparatus of the character described, a sloping channel, means for heating the same, an ore supply, means for successively picking the ore up carrying it forward in line with the channel and allowing it to fall during its passage through the channel, and means for discharging gas into the falling ore. 90
10. In an apparatus of the character described, a sloping channel, means for heating the same, an ore supply, means for successively picking the ore up and allowing it to fall during its passage through said channel, and means for discharging gas from opposite sides into the falling ore. 95
15. In an apparatus of the character described, a sloping channel, means for heating the same consisting of a furnace adjacent to the lower end thereof and provided with a flue extending beneath and separate from the channel, an ore supply, means for picking the ore up and carrying it forward in line with the channel and allowing it to fall during its passage through the channel, and means for discharging gas into the falling ore. 100
20. In an apparatus of the character described, a sloping channel, means for heating the same consisting of a furnace adjacent to the lower end of the same and provided with a flue extending beneath the channel, an ore supply at the upper portion of the channel, means for picking the ore up and allowing it to fall during its passage through the channel, and means for discharging gas into the falling ore. 105
25. In an apparatus of the character described, a sloping channel, means for heating the same consisting of a furnace adjacent to the lower end of the same and provided with a flue extending beneath the channel, an ore supply at the upper portion of the channel, means for picking the ore up and allowing it to fall during its passage through the channel, and means for discharging gas into the falling ore from opposite sides. 110
30. In an apparatus of the character described, a sloping channel, means for heating the same consisting of a furnace having a flue extending contiguous to the channel, a gas generator, means for feeding ore to the channel, means for agitating the ore and carrying the same forward in line with the channel, and a passage lying within the furnace flue and leading from the generator and discharging the gas into the agitated ore. 115
35. In an apparatus of the character described, a sloping channel, means for heating the same consisting of a flue exterior thereto, an ore supply, means for agitating the ore and carrying the same forward in a plane parallel to the channel, means for heating air, means for supplying air to the heating means, and a passage arranged within the heating flue serving to convey the heated air to the channel and discharge the same into the heated ore. 120
40. In an apparatus of the character described, a sloping channel, means for heating the same, an ore supply, means for agitating the ore in its passage through the channel, a chamber, a pipe for supplying steam thereto, a fan for supplying air thereto, and a passage leading from the chamber to the channel and so arranged as to discharge the gaseous fluids into the agitated ore. 125
45. In an apparatus of the character described, a sloping channel, means for feeding ore into said channel, means exterior to said channel for heating the floor of the same, a wheel rotatably disposed within the channel, and peripheral scoops or buckets on said wheel adapted to pick up the ore and carry the same over and allow it to fall upon the heated floor. 130
50. In an apparatus of the character described, a sloping channel having a concave shelf formed therein, means for feeding ore onto said concave shelf, means for heating the channel, a wheel rotatably disposed within the channel above the concave shelf, and peripheral scoops or buckets on said wheel adapted to pick up the ore from the concave shelf and carry the same over and allow it to fall. 135
55. In an apparatus of the character described, a sloping channel having a concave shelf formed therein, means for feeding ore onto said concave shelf, means for heating the channel, a wheel rotatably disposed within the channel above the concave shelf, and peripheral scoops or buckets on said wheel adapted to pick up the ore from the concave shelf and carry the same over and allow it to fall, a shaft consisting of a plurality of sections having shoulders formed at their contiguous extremities, the shoulder of one section secured to the shoulder of the adjacent section, and a heat-resisting medium interposed between the shoulders whereby the transmission of heat longitudinally of said shaft is prevented. 140
60. In an apparatus of the character described, a sloping channel having a concave shelf formed therein, means for feeding ore onto said concave shelf, means for heating the channel, a wheel rotatably disposed within the channel above the concave shelf, and peripheral scoops or buckets on said wheel adapted to pick up the ore from the concave shelf and carry the same over and allow it to fall, a shaft consisting of a plurality of sections having shoulders formed at their contiguous extremities, the shoulder of one section secured to the shoulder of the adjacent section, and a heat-resisting medium interposed between the shoulders whereby the transmission of heat longitudinally of said shaft is prevented. 145
65. In an apparatus of the character described, a sloping channel, means for heating the same, an ore supply, means for successively picking the ore up and allowing it to fall during its passage through said channel, means for discharging gas from opposite sides into the falling ore, a drying chamber provided with oppositely disposed deflecting plates, and means for withdrawing from the upper portion of the chamber the gases from the roasting channel. 150
70. In an apparatus of the character described, a sloping channel forming a roasting chamber, a furnace disposed adjacent to the lower end of the same, a smoke discharge flue leading beneath the channel, an ore discharge, a gas generator, pipes leading from the gas generator and discharging into the channel from opposite sides, a series of concave shelves forming the floor of said channel, a series of wheels rotatably mounted within the channel above the
75. In an apparatus of the character described, a sloping channel, means for heating the same, an ore supply, means for successively picking the ore up and allowing it to fall during its passage through said channel, means for discharging gas from opposite sides into the falling ore, a drying chamber provided with oppositely disposed deflecting plates, and means for withdrawing from the upper portion of the chamber the gases from the roasting channel. 155

concave shelves, peripheral scoops or buckets on the wheels and adapted to pick the ore up from one concave shelf and carry it over and allow it to fall in line with the gas discharge pipes, a drying chamber forming a continuation at the upper end of the roasting channel and provided with oppositely disposed deflecting plates, an ore supply at the upper end of the drying chamber, a pipe leading from the drying chamber, a precipitating tank communicating with said last named pipe, a steam pipe com-

municating with said tank, a pipe leading therefrom to an acid chamber and means for withdrawing the acid formed therein. 10

In testimony whereof I affix my signature to this specification, in the presence of two witnesses.
